UNITED STATES PATENT OFFICE.

DAMON R. THROOP, OF DAVIS, CALIFORNIA.

SCRAPER.

1,330,359.

Specification of Letters Patent. Patented Feb. 10, 1920.

Application filed October 14, 1918. Serial No. 257,989.

To all whom it may concern:

Be it known that I, DAMON R. THROOP, a citizen of the United States, residing at Davis, in the county of Yolo and State of California, have invented a new and useful Scraper, of which the following is a specification.

The subject of this invention is a scraper intended for use in leveling and checking land, and more especially useful in preparing land for irrigation.

The main object of the invention is to provide a scraper, capable of dumping earth in ridges or checks, with means for raising and lowering the scraper blade when desired so that earth may be delivered thereunder and spread to a desired thickness.

Another object of the invention is the provision of means for holding the scraper blade in any desired position.

The invention also contemplates generally improving the construction and enhancing the utility of wheel supported scrapers.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

A practical structure for carrying out the invention is shown in the accompanying drawings, wherein:

Figure 1 is a view in side elevation of a scraper constructed in accordance with the invention, a portion broken out for convenience and economy of space;

Fig. 2 is a plan view of the same;

Fig. 3 is a view in rear elevation, portions removed;

Fig. 4 is a view in rear elevation of the scraper blade.

Referring to the drawings by numerals of reference:—

In carrying out the invention there is provided a frame formed of two bars, 1, preferably of channel iron, which are arranged for a portion of their length in spaced parallelism and then converge forwardly to the meeting ends 2 which are disposed

angularly to the converging portions that the portions 2 may be in contact longitudinally. A draw head 3 is secured by bolts 4, or otherwise, to the ends of the portions 2 of the bars 1.

To the parallel portions of the bars 1 are secured, by rivets 5 or the like, the flooring members or boards 6, which form a platform upon which the operator of the machine may stand. A cross brace 7 is secured between the bars 1, at the forward end of the platform, to lend proper rigidity and strength to the structure.

An axle 8 extends through apertures formed in the bars 1, between the ends of the parallel portions thereof, and the axle is arranged transversely of the machine with its ends extending laterally of the bars 1. Mounted to rotate on the extending ends of the axle 8 are the supporting wheels 9 which render transportation of the device less difficult.

The forward ends of side beams 11, which may also be of channel iron, have pivotal engagement with the extending ends of the axle 8, and are held thereon in spaced relation to the wheels by collars 10. The rear ends of these side beams 11 are apertured to pivotally receive the ends of the shaft of a scraper blade. This scraper blade is composed of a shaft 12, preferably formed of gas pipe or other hollow stock material, and extending longitudinally of the shaft, and located at diametrically opposite positions thereon, are the boards or planks 13, which are bound rigidly in place upon the shaft by the straps 14, of metal or the like, which are secured transversely of the scraper blade by means of rivets or the like. The remote longitudinal edges of the planks 13 are beveled and a metal strip 15 is secured along each cutting edge by rivets or otherwise for the purpose of protecting the cutting edge from injury.

The ends of the shaft 12 extend laterally beyond the side beams 11, and to these ends are rigidly secured the pawls or cross arms 16, clamps 17 being provided for the purpose of securing them in place. The cross arms 16 are positioned sixty degrees apart, and a like angular distance from the scraper blade so that, when the blade is released to rotate, as will be hereinafter described, the

ends of the cross arms will successively engage the ground and return the blade to proper operative position. The arm 16 may be kept in proper spaced relation to the 5 side beams 11 by means of spacing collars 18.

In order that earth collected before the 10 scraper blade may be properly retained in place and prevented from escaping beyond each end of the blade, retaining plates 19, formed of boiler plate or the like, are suitably secured to the side beams 11 in position to have their lower edges in contact with the ground when the scraper blade is in operative position.

Mounted transversely of the rear ends of the bars 1, is a beam 20, to which are secured and from which rise the uprights 21, preferably three in number, and located respectively at each end and near the longitudinal center of the beam 20. Struts or brace bars 22 are secured to the upper ends of the end uprights 21, and extend downwardly and forwardly therefrom, and the 25 forward ends of these struts are secured to braces 23, which are secured to and extend from the bars 1 and have their rear ends apertured to receive the ends of the axle 8. These braces 23 serve to support and brace 30 the axle to resist the strain due to cutting and transporting earth.

Journal boxes 24 are secured to the uprights 21, near the upper ends thereof, and serve as a journaling means for a horizontally disposed shaft 25. A hand wheel 26 is rigidly secured on the shaft 25, at a point between the ends of the shaft, and a brake drum 27 is rigid on the shaft in juxtaposition to the wheel. A brake strap or band 28 40 has one end secured to a bracket 29, which bracket is secured to the central upright 21, and passes about the drum with its other end connected by a link 30 to a treadle 31, one end of which treadle is pivotally connected to the central upright 21 adjacent its lower end. As will be readily understood from the foregoing, the shaft 25 may be rotated by means of the hand wheel 26, and the shaft held in any rotated position by pressure of 45 the foot on the treadle 31. This operation is had for the purpose of raising or lowering the scraper blade and its supporting frame through means of the mechanism now to be described.

50 The ends of the shaft 25 extend laterally beyond the end uprights 21, and pinions 32 are rigidly secured on these extending ends. The pinions 32 mesh with racks 33, which are formed longitudinally of rods 34, the lower 55 ends of which rods have pivotal connection with blocks 35, secured to the rear ends of the side beams 11. Revolution of the pinions will, therefore, tend to raise or lower the rods 34, as the case may be, and so raise 60 or lower the scraper. In order that the racks

33 may be kept in mesh with the pinions 32, bifurcated arms 36 are loose on the ends of the shaft 25, and rollers 37 are journaled on the prongs of the arms and contact that edge of the rods 34 remote from the racks 33.

70

For the purpose of retaining the scraper blade in operative position and releasing the same at will, a lever 38 is pivotally secured to the central upright and has a treadle 39 formed on its forward end to be engaged by the foot of the operator, while on its under side, and toward its rear end, is provided a shoulder 40, which forms a catch against which the scraper blade strikes and which restrains the blade against rotation. A retractile spring 41 has one end connected to the under face of the lever 38, rearwardly of its pivot point, and its other end secured to the beam 20, or other suitable part of the framework of the machine, and serves to retain the lever in scraper blade engaging position.

80

In practice the machine is operated in the following manner:—

A tractor, or other source of motive power, 90 is hitched to the draw head 3 for the purpose of transporting the scraper over the field or land which is to be operated upon.

The scraper blade is set as shown in Fig. 1 and the machine drawn forward, which 95 will cause earth to accumulate before the blade. If it is desired to deposit the earth in a thin layer over certain parts of the work, the hand wheel 26 is turned until the scraper blade is raised the required distance, 100 when the earth will escape beneath the scraper blade and will be spread thereby.

When it is desired to deposit the earth in ridges to form checks, or for other purposes, the scraper blade is released by pressing downwardly on the lever 38. When the scraper blade is released, the weight of earth before the blade will cause the blade to rock and release the earth. When this takes place the ends of the cross arms 16 engage 110 the earth and cause the blade to rock to again assume operative position.

Having thus described the invention, what is claimed as new and sought by Letters Patent, is:—

115

1. A scraper, including a transportable frame, a scraper blade mounted for rotation in the frame, releasable means for locking the blade against rotation, angularly disposed radial arms revoluble with the blade 120 and engageable with the ground for automatically restoring the blade, when released, to operative position, and means for raising and lowering the blade.

2. A scraper including a movable structure, side beams pivotally connected to said structure, a shaft journaled therein, a reversible scraper carried by and revoluble with the shaft, radial arms secured to the shaft and revoluble therewith, said arms 125

125

130

and the scraper being disposed out of trans-
verse alinement and adapted successively to
engage the ground, means engaging one
edge of the scraper for holding the shaft
5 and scraper against rotation, means under
the control of the operator for raising and
lowering the shaft and side beams, and
means for releasing the scraper, said scraper
and its arms constituting means for rotat-

ing the shaft and inverting the scraper when 10
the scraper is released.

In testimony that I claim the foregoing
as my own, I have hereto affixed my signa-
ture in the presence of two witnesses.

DAMON R. THROOP.
